UNITED STATES PATENT OFFICE.

ROBERT KENT, OF BROOKLYN, NEW YORK.

ROLL FOR BENDING PLATE METAL.

SPECIFICATION forming part of Letters Patent No. 325,677, dated September 8, 1885.

Application filed January 18, 1884. (No model.)

To all whom it may concern:

Be it known that I, ROBERT KENT, of Brooklyn, in the county of Kings, State of New York, have invented certain Improvements in Rolls 5 for Bending Plate Metal, of which the following is a specification.

This invention relates to that class of machinery for bending plate metal into curved forms, which is commonly designated as "vertical plate-bending rolls."

Its object is to provide a small, strong, and effective apparatus of the kind, which will be capable of steady and noiseless motion and of more than ordinarily effective action in its 15 operation upon the plates to be bended.

Figure 1 is a front elevation of the apparatus embracing my said invention. Fig. 2 is a top view of the same. Fig. 3 is a horizontal sectional view taken in the line *xx* of Fig. 1. Fig. 20 4 is a horizontal sectional view taken in the line *yy* of Fig. 1. Fig. 5 is a vertical sectional view taken in the line *zz* of Fig. 2. Fig. 6 is another sectional view, taken in the line *vv* of Fig. 5. Fig. 7 is a sectional view of certain 25 parts, also shown in Fig. 3, taken in line *uu* of said Fig. 3.

A, B, and C are three rolls, and D and E are respectively the upper and lower parts of the strong frame which supports the working 30 30 of the apparatus.

The roll A has its upper end working in suitable bearings in the upper part, D, of said frame. The journal of said roll A, at the lower end thereof, is provided with a spur- 35 pinion, *a*, and works in a suitable bearing in the frame E, the lower end thereof resting on a suitable bearing, *Q*, as shown in Figs. 1 and 7. The said roll A is vertically—that is to say, longitudinally—grooved, in order that it 40 40 may more effectually grip upon the surface of the sheet metal passed in contact therewith during the bending of the said sheet metal, as hereinafter set forth.

The roll B has its upper end supported in a 45 bearing at *b*, the said upper end of the roll B being of the same diameter as the main portion thereof, in order that the said roll may be elevated longitudinally from its place on occasion by means of a bail or handle, *c*, at its 50 upwardly-projecting extremity. The lower end of said roll B works through a suitable

bearing in the lower part, E, of the frame of the machine, and is provided with a squared shank, *d*, which fits into a corresponding socket formed axially in the spur-pinion *e*, which 55 gears with the spur-pinion *a*, so that the rotation of the said spur-pinion *a* in the turning of the roll A will produce a corresponding rotation in the opposite direction of the roll B. From the spur-pinion *e* extends upward through the 60 frame E a sleeve, *n'*, as indicated in Fig. 7, and into the squared interior of this sleeve fits the square shank *d* of said roll, so that the outside of the sleeve forms the bearing for roll B. The spur-wheel is kept in place by a suitable key. 65 At *m'* is a strap placed under the spur-pinion *e* to prevent its falling down when the roll B is lifted out of its place.

Upon the shaft or journal of the roll A, below the spur-pinion *a*, is a bevel-wheel, *e'*, into 70 which gears a worm, *f*, on the horizontal shaft F, which works in suitable bearings provided in the frame of the machine, and which has at one end suitable pulleys for giving rotation in the requisite direction to the shaft F, as 75 indicated in G G' G''.

The roll C has its bearings in boxes placed in slots *g h* in the parts D E of the frame, which said boxes are operated by two screw-shafts, H and I. These screw-shafts are provided 80 with nuts L, which work in suitable bearings, N, arranged in respectively the upper and lower parts, D and E, of the frame, and are provided with shoulders *m* and *n*, the purpose of which is to keep the nuts from moving in 85 lengthwise direction. Said nuts form the hubs of the bevel-wheels J.

A vertical shaft, G*, supported in bearings *a' b'*, is provided with two pinions, *r*, one of which gears into the upper bevel-wheel, J, 90 while the other gears into the lowermost of the said bevel-gears J. The said shaft G* is provided with radial arms, whereby it may be turned in one direction or the other at will, so that by turning the said shaft in one direction 95 or the other a horizontal movement may be transmitted to the roll C to change its distance from and relation to the other rolls, A B. By this arrangement of parts the roll is fed uniformly at top and bottom to the other rolls, A 100 B, as just explained.

In performing what is termed "cone-

shaped" work, one or the other of the pinions *r* is thrown out of gear with its adjacent bevel-gear *J*, according as the cone has to be inverted or otherwise. To provide for this throwing out of gear of either bevel-pinion the pinions are attached to the shaft by means of the usual spline and groove. The prolonged part of the hub of each of said pinions is provided with a circumferential groove, *p*, in which works the fork-shaped end of a suitable lever, *w*, arranged to actuate the same.

The sheet metal is fed into the machine from the rear side, as indicated by the arrow in Fig. 3, and in those cases where it is bent into a cylindirical form, thereby being passed around the roll *B*, the latter is elevated by the shackle or bail *e*, as hereinbefore explained, thereby permitting the removal of the sheet-metal cylinder.

20 What I claim as my invention is—

1. In "vertical plate-bending rolls," so called, the longitudinally-grooved roll *A*, and the vertically-removable roll *B*, in combination with the top and bottom bearings, gearing for rotating the rolls *A*, *B* in unison, the roll *C*, 25 and a screw for adjusting the roll *C* in a horizontal direction, all substantially as and for the purpose herein set forth.

2. The combination of the worm-shaft *F*, worm-wheel *e'*, pinions *a* and *e*, shaft *G**, 30 bevel-pinions *r*, bevel-gears *J*, and screw-shafts *H* and *I*, in combination with the slotted top and bottom portions, *D* and *E*, of the frame, the vertical rolls *A*, *B*, the vertical roll *C*, and the sliding bearings of said roll *C*, all substantially as and for the purpose herein set forth. 35

ROBERT KENT.
